EXTENSIBLE DISPLAY SHELF UNIT FOR PACKAGES

Fred Howard, New York, N.Y., assignor to Copeland
Self-Selectors Inc., New York, N.Y.

Application December 13, 1957, Serial No. 48,889

Term of patent 3½ years

(Cl. D80—10)

Fig. 1 is a perspective view of an extensible display shelf unit for packages, showing my new design in extended position.

Fig. 2 is a right side elevational view thereof as shown in Fig. 1 but on a slightly reduced scale; and

Fig. 3 is a right side elevational view of the unit in retracted position.

I claim:

The ornamental design for an extensible display shelf unit for packages substantially as shown.
